UNITED STATES PATENT OFFICE.

ISAAC F. GILES, OF YONKERS, NEW YORK, ASSIGNOR TO ILEITE ELECTRIC MANUFACTURING CORPORATION, OF TUCKAHOE, NEW YORK, A CORPORATION OF NEW YORK.

MULTIPLE-SOCKET ELECTRIC PLUG.

Application filed February 13, 1925. Serial No. 8,888.

This invention pertains to multiple socket electric fixtures and particularly to a two-way socket, wherein the casing comprises molded electrical insulating material. One of the difficulties arising from the manufacture of fixtures having molded casings is the liability of the casing to crack, particularly in the region adjacent the metallic parts which are embedded within the casing during the forming operation. The present invention is directed toward the provision of a fixture which overcomes the difficulties arising during the manufacture of a molded casing, and which tends to reduce the percentage of breakage during the manufacturing operation.

The preferred form for carrying out my invention is illustrated in the drawings wherein Fig. 1 is a plan view of an electric fixture embodying my invention; Fig. 2 is an end elevation of the fixture shown in Fig. 1; Figs. 3 and 4 are sections taken on planes indicated by the lines 3—3 and 4—4 respectively in Fig. 2; Fig. 5 is a perspective view illustrating an electrical connecting piece, and Fig. 6 is a perspective view showing portions of the fixture removed from the casing.

I have illustrated my invention in connection with a casing 10, of electrical insulating material, molded to the desired shape. As shown, however, the casing has outwardly facing openings 11 and 12 in the nature of sockets which are separated by a wall 13 which is integral with the casing. The casing also has passageways 14 and 15 which lead outwardly from the openings 11 and 12 respectively, and has a passageway 9 which extends through the wall 13 and provides communication between the sockets 11 and 12.

Electric current may be brought into the casing through contact members 16 and 17 which have opposite polarity and are shown as extending into the passageways 14 and 15 respectively and as projecting beyond the outer surface of the casing. As indicated, a part of the member 16 is exposed within the socket 11 and is electrically connected by a member 18 to a threaded shell or socket 19. The socket preferably sets closely within the pocket.

A socket 20 similarly formed to the socket

19 is disposed within the pocket 12 but is electrically insulated from the plate 17. The two socket members, however, are electrically connected by a plate 21 which is disposed within the passageway 16. This plate has upturned ends indicated at 22 and 23 which are slightly yieldable with reference to the body of the plate, wherefore an effective electrical connection can be made between the socket members whenever the plate is embedded within the passageway 16. The plate 21 may be positioned by inserting it endwise into the passageway 8 through the pocket opening 12 before the socket member 20 is inserted within the casing. The ends of the plate 21 therefore engage the outer surfaces of the socket members and are prevented from moving out of the casing by reason of the fact that the yieldable ends of the plate 21 engage the corrugated outer surface of the socket members.

The socket member 19 is prevented from rotating within the casing by the connection 18 between the member and the blade 16. Accordingly to prevent the socket member 20 from rotating within the casing I have shown the casing as having a lug 24 which projects into an opening 25 within the flange portion 26 of the member 20.

The member 17 has a polarity opposite to that of the plate 16. Accordingly the plate 17 must be electrically insulated from the socket members 19 and 20. To this end I have shown a sleeve 30 which is embedded within the wall 13 in such manner that the axis of the sleeve is substantially aligned with the axis of the socket members 19 and 20 respectively. The interior of the sleeve is threaded to receive contact screws 31 and 32, the heads of which extend into the respective socket members and are electrically insulated therefrom. The screw heads therefore form one terminal while the socket members form another terminal for each outlet.

From the foregoing description it will be evident that my invention provides a two-way socket which obviates the necessity for embedding metallic parts within the casing during the moulding operation. This has a tendency to reduce the loss resulting from breakage of the casing during the manufacture thereof. It will further be evident

that a device made in accordance with my invention is quite simple in construction and is durable in use.

Having thus described my invention, I claim:

1. In a device of the character described, the combination with a casing comprising electrical insulating material having pockets opening outwardly from the ends thereof, and having an integral wall disposed intermediate the pockets, there being a passageway leading from each pocket, a threaded socket mounted within each pocket, a contact blade mounted in each passageway, means respectively connecting one of the sockets to one of said blades, and a yieldable electric conductor for providing an electrical connection between said sockets, and central contacts within the sockets electrically connected with the other blade.
2. In a device of the character described, the combination with a casing comprising electrical insulating material having substantially cylindrical pockets opening outwardly therefrom, the axis of one pocket being aligned with the axis of the other pocket, there being a wall separating the pockets, a passageway leading through the casing from each pocket, a contact blade in each passageway, a socket member in each pocket, said casing having a passageway off-set from the pocket and providing communication therebetween, a connecting member having yieldable ends engaging the respective socket members to provide an electrical con-

nnection therebetween, means for electrically connecting one of the blades to one of the socket members, base terminals electrically connected to the other blade, and means for insulating the last mentioned blade from 40 said socket members.

3. In a device of the character described, the combination with a casing having pockets therein, said pockets opening in opposite directions and being substantially in alignment, said casing having a passageway offset from the pockets and providing communication therebetween, a socket member disposed in each pocket, and a spring metal current carrying member disposed in said 50 passageway and providing an electrical connection between the socket members.

4. In a device of the character described, the combination with a casing having pockets therein opening outwardly and having a 55 passageway providing communication between the pockets, a socket member disposed in each pocket, and a contact strip disposed in the passageway, said strip having the ends thereof turned to back upon itself, the ends of said strip being in engagement with the outer surfaces of the socket members, whereby movement of the strip with reference to the members is prevented, said strip functioning to provide an electrical connection 60 between said members.

In testimony whereof I hereunto affix my signature.

ISAAC F. GILES.
